UNITED STATES PATENT OFFICE

1,984,767

PLAYGROUND APPARATUS

Willard H. Shaffert, Boston, Mass.

Application May 31, 1932, Serial No. 614,548

2 Claims. (Cl. 189—36)

This invention relates to new and novel playground apparatus adaptable for sports, recreation, athletics; and to the design and construction thereof.

5 It will be understood by those familiar with the art to which this invention appertains, that the collapse of most playground and similar equipment is due to the concealed corrosion and decomposition at the ground level and base line 10 of the material from which such equipment is made.

The objects of this invention are to eliminate concealed corrosion and decomposition; to eliminate the condensation of moisture and the expansion and contraction of construction material; to eliminate the hazard of apparatus collapse with resulting bodily injury to the users; to provide new and novel apparatus design and construction; to minimize apparatus cost, both 20 initial and maintenance; to provide a new and novel means of bracing and strengthening such apparatus; to minimize the space required for a given amount of equipment; to provide a new and novel construction for vertical beams, horizontal beams, diagonal braces, and means for joining, connecting, and setting up of the same; to provide a new and novel construction utilizing standard H beams, T beams, and angle iron; to provide a simplified construction which renders 25 possible perfection in assembly by an ordinary workman without the need of those special tools as are ordinarily associated with assembly jobs; to provide new and novel adjustment means 30 adaptable for relevelling and reassembling the equipment; and to provide the various other advantages and results made evident from the following specification.

I accomplish the objects of this invention by utilizing standardized H beams, T beams, angle 40 irons, so called, and bolts, all preferably of steel, in combination with re-enforced concrete foundations, but it will be understood that any suitable material may be used. The vertical beams or uprights are preferably H beams, so called. 45 The horizontal beams are preferably T beams, so called, and the vertical and diagonal braces are preferably of angle iron, so called. A minimum amount of preparation of the H beam is required and is performed by cutting out a portion of the web of the H beam so as to leave the flanges of the H beam extending beyond the cut away portion of the web. The 50 extending portions are then bent inward in the direction of each other, at the point where

the web is cut away, and the extreme ends are in a position parallel to each other and parallel with the flanges of the H beam where the web has not been cut away. A series of holes are then placed in the extension ends to provide 5 for means of assembling, securing and adjusting, and to receive the bolts with which the various parts of the apparatus are secured together.

The apparatus is diagonally braced at the top against end motion by short angle irons which may be optionally placed outside or inside the vertical H beams. The angle iron used for the bracing purpose being connected with the H beam upright near its top, and to the T beam horizontal near the upright. The vertical H beams are also braced by vertical angle iron braces extending therefrom at their upper portions to the ground. The vertical angle iron braces, extending from the upper portion of the H beam to the ground, are set flat side down 10 ward so as to avoid and make it uncomfortable for users to climb and hang thereon. The horizontal T beam is placed with its flange down 15 in the assembly. A series of holes are then placed in this lower flange of the T beams at 20 various intervals for the purpose of affording opportunity for hanging swings, acrobatic rings, climbing ladders, ropes, etc., or other gymnastic or recreational equipment thereto. A wide 25 variety of equipment may thus be assembled with 30 minimum cost with the assurance that at no time will there be any interior deterioration, decomposition, and resulting collapse.

Referring to the accompanying drawings which form a part of this specification and in 35 which similar letters of reference refer to similar parts throughout the various view, Figure 1 shows an end view of one embodiment of my apparatus. Figure 2 shows an enlarged detail view of the various component parts in juxtaposition which are joined to form the upper portion of the apparatus shown in Figure 1. Figure 3 shows a cross sectional view of the vertical upright on the line 3—3 in Figure 1. Figure 4 shows a cross sectional view of the vertical angle iron braces on the line 4—4 in Figure 1. Figure 5 shows a side view of the apparatus 40 shown in Figure 1. Figure 6 shows a side view in another embodiment of my apparatus with the diagonal angle iron braces from the vertical 45 uprights to the horizontal beams set as outside braces rather than as inside braces shown in Figure 5.

Referring again to the drawings, A shows the vertical uprights which are formed as herein 50 55

stated from H beams or I beams. B shows the vertical angle iron braces extending from the top of the H beam to the plane upon which the apparatus is erected. C shows the horizontal T beam supported at the top of the vertical H beam upright. A² shows the reenforced foundation upon which and in which the vertical upright is supported. B² shows the foundation in and on which the angle iron braces are supported. C² or C³ show holes in the T beam horizontal C which are adaptable to register with the holes A² in the vertical upright A. A³ shows where the web of the vertical H beam upright is cut away, and the flanges A⁴ are bent inwardly towards each other. A⁵ shows the point on the flanges at which they are again bent into position parallel to each other as at A⁶. A⁷ shows holes in the extending portions A⁴ adaptable to register with the holes B² and B³ and which holes are adaptable to receive the bolts B⁴, which bolts are secured in position by the nuts thereon B⁵. The horizontal beam C is secured in erected position by the bolts C⁴ with the nuts C⁵ thereon. C⁶ shows the holes in the lower portion of the T beam horizontal to which the swings C⁷ or other gymnastic or recreational apparatus are secured.

Referring again to Figure 5, the short diagonal angle iron braces D, from the T beam horizontal to the vertical uprights, are placed in what may be called inside position in contradistinction to the outside position D² shown in Figure 6.

Adjustment means to provide for the re-leveling of the horizontal T beams and bringing into perpendicular the vertical H beams, that the attached apparatus may swing to and from a horizontal plane, are provided by a series of holes such, for instance, as C² or C³ in the T beam horizontal C, in combination with the holes A² in the vertical upright A and the bolts C⁴ and nuts C⁵ passing through such holes when properly registered. In event it is desired to elevate the T beam horizontal C at one end, the holes C³ are registered with the holes A² and the bolt C⁴ inserted therethrough. And in event it is desired to lower the T beam horizontal C at one end, the holes C² are registered with the holes A² and the bolt C⁴ placed therethrough when so registered. Similar means of adjustment to make vertical H beams perpendicular are provided at the upper end of the vertical angle iron braces B, and comprise a series of holes therein designated as B² or B³, adaptable to register with the holes A⁷ on the H beam vertical upright A. Likewise a series of holes may be

placed near the point of contact with the diagonal angle iron braces D or D² in the web of the vertical H beam upright so as to provide for any adjustment desired when any one of said holes register with the holes in the angle iron braces D or D². Or optionally a series of holes may be placed in the diagonal angle iron braces rather than on the vertical upright beams, or a series of adjustment orifices may optionally be placed on the T beam horizontal. Optional adjustment means to provide for repositioning the short diagonal iron braces to meet the resultant change in the re-levelling of the apparatus is had by oversized holes in the flange portion of the T brace, and oversized bolts and nuts used thereon.

While I have illustrated and described a preferred construction for carrying my invention into effect, this is capable of variation or modification without departing from the spirit of the invention. I therefore do not wish to be limited to the exact details of construction herein set forth, but desire to avail myself of such variations and modifications as come within the scope of the appended claims.

The structure herein described is adaptable for all playground, gymnasium, and recreational apparatus such as swings, see-saws, slides, etc. My improved apparatus may be grouped in units or assembled in extended formation as desired. Parallel vertical uprights may be utilized upon which to mount a horizontal bar or bars for use with well recognized exercises.

Having thus described my invention, I claim as new and desire to secure by Letters Patent of the United States of America:—

1. An apparatus of the class described, comprising spaced beams having their upper ends provided with terminal flanges bent to provide inclined portions and parallel spaced portions, a cross beam engageable between the parallel spaced portions, and brace bars having parts thereof secured in intimate engagement with the inclined portions of said beams.

2. An apparatus of the class described, comprising a pair of spaced vertically disposed beams including webs and flanges, the flanges extending upwardly from the webs and bent to provide inwardly inclined portions and parallel spaced portions, a cross beam including a web engageable between said parallel portions, brace bars having their upper ends engaged on said inclined portions and secured thereto to maintain said bars in inclined relationship with respect to the said beams.

WILLARD H. SHAFFERT.
